United States Patent Office

Des. 203,801
Patented Feb. 22, 1966

203,801

SINK

Harold R. Benson, Lombard, Ill., assignor to The Nuarc
Company, Chicago, Ill., a corporation of Illinois

Filed Jan. 16, 1964, Ser. No. 78,227

Term of patent 14 years

(Cl. D4—2)

FIG. 1

Des. 203,801

PAGE 2

FIG. 3

FIG. 2

Des. 203,801

PAGE 5

FIG. 4

FIG. 5

FIG. 1 is a perspective view of a sink, showing my new design;

FIG. 2 is a reduced front elevational view thereof;

FIG. 3 is a plan view thereof;

FIG. 4 is a side elevational view thereof; and

FIG. 5 is a rear perspective view thereof.

The side opposite that shown in FIG. 4 is a mirror image thereof.

I claim:

The ornamental design for a sink, substantially as shown and described.
